TRANSFER TAIL APPLYING MEANS

Hector L. Ayala, Ocotlan, Mexico, assignor to
Celanese Corporation of America, New York,
N. Y., a corporation of Delaware

Application December 3, 1949, Serial No. 130,909

10 Claims. (Cl. 57—75)

1

This invention relates to means for applying a magazine wrap or transfer tail to a yarn package and relates more particularly to a novel means adapted to be employed in connection with yarn winding and twisting apparatus for applying said magazine wrap or transfer tail during winding and twisting operations.

As commonly understood in the textile art, a magazine wrap or transfer tail is a portion of the inner end of the first yarn wound on a yarn support, which is so disposed as to be positively secured during the winding of the remainder of the yarn package, yet freely available for tying directly to the outer end of the yarn on another yarn package. The purpose of providing a magazine wrap or transfer tail is to enable an uninterrupted flow of yarn to be maintained from a depleted yarn package to a full package adjacent thereto, as in a creel or other yarn package holder on which both yarn packages are supported.

An object of this invention is the provision of a novel auxiliary means, cooperating with yarn winding devices whereby yarns are wound on to yarn package supports, adapted to cause a portion of the yarn wound thereon to wind on to said yarn package support at a point adjacent to the main windings so that said portion is readily available for use as a magazine wrap or transfer tail.

Another object of this invention is to provide an improved means adapted to guide a yarn on to a rotating yarn package support while the yarn package support is rotating at high speeds, as in continuous spinning processes wherein artificial filaments are spun, so that a portion of said yarn will be available for use as a magazine wrap or transfer tail.

Other objects of this invention, together with certain details of construction and combinations of parts, will appear from the following detailed description and the accompanying drawing.

In the accompanying drawing wherein a preferred embodiment of my invention is shown,

Fig. 1 is a side elevational view of a portion of a yarn winding device including a spinning ring and traveler, a driven spindle, a yarn package support carried thereby, and the novel auxiliary means of my invention cooperating therewith for applying a magazine wrap or transfer tail to said yarn package support, and

Fig. 2 is a perspective view of said novel auxiliary means including a slotted gripping means and a guide means cooperating therewith for the application of said magazine wrap or trans-

2

fer tail at the base of the yarn package support. Like reference numerals indicate like parts throughout both views of the drawing.

Referring now to the drawing, and more particularly to Fig. 1, a yarn 3, passing through a pigtail yarn guide 4, which may be supported in any suitable manner (not shown) and coming from any suitable source of supply, such as a metier or spinning cabinet (not shown) in which 5 said yarn may be formed by an extrusion process, for example, is passed downwardly and is threaded through a traveler 5 mounted on a spinning ring 6. A ring holder 7 which is normally mounted on a vertically reciprocable ring rail (not shown) 10 supports the spinning ring 6. When yarn 3 is 15 thrown on to a rotatably driven yarn package support 8 in the usual manner, the vertically reciprocating movement of spinning ring 6 distributes the yarn windings on said yarn package 20 support 8 to form a yarn package 9. The rotation of yarn package support 8 is effected by means of a spindle 10 which frictionally engages the interior of said yarn package support 8. Spindle 10 is provided with a whorl 11 frictionally 25 engaged by a drive belt 12, the motion of which serves to rotate spindle 10 at high speed and to cause yarn package support 8 to take up yarn 3. The action of the traveler on said vertically reciprocating spinning ring serves to impart the desired twist to the yarn being wound while the movement of the ring serves to distribute the yarn windings.

Without any guide means being provided to direct yarn 3 on to yarn package support 8 at 30 a point on the base thereof separate from the windings forming yarn package 9 when yarn 3 is initially thrown on to yarn package support 8 as winding is commenced, no magazine wrap or transfer tail will be available and the usual yarn 35 package 9 is formed.

In accordance with my invention, however, I provide a yarn gripping means and a novel yarn guide means cooperating therewith so that yarn 40 3 will be thrown on to yarn package support 8 automatically in forming yarn package 9 and a portion of said yarn 3 will wind on to yarn package support 8 separate from the main winding so as to be available as a magazine wrap or transfer tail.

In accordance with my invention, a substantially spiral guide 13 is fixed to a supporting bracket 14 which is suitably attached to a portion of the machine frame (not shown) so that said guide 13 is in a fixed position relative to 45 spindle 10. Guide 13 encircles the spindle 10 at

a point just above the base of the yarn package support 8 which is frictionally mounted thereon. Below guide 13 is provided a collar 15 fixed to and rotated by spindle 10. Collar 15 contains a narrow slot 16 which serves to grip and retain an end of yarn 3. To provide the desired magazine wrap or transfer tail when winding is initiated, employing the novel device of my invention, yarn 3 passing through pigtail guide 4 and traveler 5 is drawn downwardly at the up-stroke of ring 6 and is pressed against the periphery of collar 15 which is, of course, rotating at high speed. During the rotation of collar 15, yarn 3 slips into slot 16 and the yarn is gripped thereby. As collar 15 continues to rotate it draws yarn 3 within the outermost convolution of spiral guide 13. Upon further rotation of collar 15, the yarn eventually passes within the innermost convolution of the guide and onto the base of yarn package support 8 to form a plurality of windings 17. The number of windings 17 which yarn 3 makes about the base of yarn package support 8 is proportional to the number of convolutions comprising said spiral guide 13, a greater number of windings being applied than there are convolutions. Only two wraps are shown in the drawing for the sake of clarity.

After passing through the several convolutions of spiral 13, yarn 3 slips out at the center and now comes under the sole control of the traveler 5 and the vertically reciprocating spinning ring 6. The spinning ring and the traveler now act to distribute the windings of yarn 3 on to yarn package support 8 in the usual way thus forming yarn package 9. The end of yarn 3 which is originally gripped in slot 16 during the winding of the yarn package 9 remains therein. When the yarn package support 8 is full, the end of yarn 3 is withdrawn from slot 16 as yarn package 9 is disengaged and removed from spindle 10. The yarn windings 17 at the base of yarn package support 8 serve as the desired magazine wrap or transfer tail.

To continue the operation, an empty yarn package support is placed on spindle 10, the end of yarn 3 held against the periphery of collar 15 in the manner described until gripped by slot 16 and the desired transfer tail and yarn package 9 again formed by the movement of yarn 3 through spiral guide 13.

It is to be understood that the foregoing detailed description is given merely by way of illustration and that many variations may be made therein without departing from the spirit of my invention.

Having described my invention, what I desire to secure by Letters Patent is:

1. In a device for producing yarn packages having a transfer tail, the combination with means including a spindle for rotating a yarn package support, a spinning ring reciprocating relative to said spindle and a traveler carried by said spinning ring, of means mounted on and rotating with said spindle for gripping a yarn end brought into contact therewith, and guide means cooperating with the yarn held by said gripping means adapted to cause the gripped yarn end to encircle the yarn package support and to wind thereon at a point spaced from the main body of yarn windings, said spaced yarn windings being available for use as a transfer tail.

2. In a device for producing yarn packages having a transfer tail, the combination with means including a spindle for rotating a yarn package support, a spinning ring reciprocating

relative to said spindle and a traveler carried by said spinning ring, of means mounted on and rotating with said spindle for gripping a yarn end brought into contact therewith, and stationary guide means cooperating with the yarn held by said gripping means adapted to cause the gripped yarn end to encircle the yarn package support and to wind thereon at a point spaced from the main body of yarn windings, said spaced yarn windings being available for use as a transfer tail.

3. In a device for producing yarn packages having a transfer tail, the combination with means including a spindle for rotating a yarn package support, a spinning ring reciprocating relative to said spindle and a traveler carried by said spinning ring, of slotted means mounted on and rotating with said spindle for gripping a yarn end brought into contact therewith in the slot, and guide means cooperating with the yarn held by said gripping means adapted to cause the gripped yarn end to encircle the yarn package support and to wind thereon at a point spaced from the main body of yarn windings, said spaced yarn windings being available for use as a transfer tail.

4. In a device for producing yarn packages having a transfer tail, the combination with means including a spindle for rotating a yarn package support, a spinning ring reciprocating relative to said spindle and a traveler carried by said spinning ring, of slotted means mounted on and rotating with said spindle for gripping a yarn end brought into contact therewith in the slot, and stationary guide means cooperating with the yarn held by said gripping means adapted to cause the gripped yarn end to encircle the yarn package support and to wind thereon at a point spaced from the main body of yarn windings, said spaced yarn windings being available for use as a transfer tail.

5. In a device for producing yarn packages having a transfer tail, the combination with means including a spindle for rotating a yarn package support, a spinning ring reciprocating relative to said spindle and a traveler carried by said spinning ring, of slotted means mounted on and rotating with said spindle for gripping a yarn end brought into contact therewith in the slot, and stationary guide means comprising a spiral cooperating with the yarn held by said gripping means adapted to cause the gripped yarn end to encircle the yarn package support and to wind thereon at a point spaced from the main body of yarn windings, said spaced yarn windings being available for use as a transfer tail.

6. In a device for producing yarn packages having a transfer tail, the combination with means including a spindle for rotating a yarn package support, a spinning ring reciprocating relative to said spindle and a traveler carried by said spinning ring, of slotted means mounted on and rotating with said spindle for gripping a yarn end brought into contact therewith in the slot, and stationary guide means comprising a spiral having a plurality of convolutions cooperating with the yarn held by said gripping means adapted to cause the gripped end to encircle the yarn package support and to wind thereon at a point spaced from the main body of yarn windings, said spaced yarn windings being available for use as a transfer tail.

7. In a device for producing yarn packages having a transfer tail, the combination with means including a spindle for rotating a yarn

package support, a spinning ring reciprocating relative to said spindle and a traveler carried by said spinning ring, of a slotted collar mounted on and rotating with said spindle for gripping a yarn end brought into contact with the periphery of said collar in the slot, and stationary guide means comprising a spiral cooperating with the yarn held by said gripping means adapted to cause the gripped yarn end to encircle the yarn package support and to wind thereon at a point spaced from the main body of yarn windings, said spaced yarn winding being available for use as a transfer tail.

8. In a device for producing yarn packages having a transfer tail, the combination with means including a spindle for rotating a yarn package support, a spinning ring reciprocating relative to said spindle and a traveler carried by said spinning ring, of a slotted collar mounted on and rotating with said spindle for gripping a yarn end brought into contact with the periphery of said collar in the slot, and stationary guide means comprising a spiral having a plurality of convolutions cooperating with the yarn held by said gripping means adapted to cause the gripped yarn end to encircle the yarn package support and to wind thereon at a point spaced from the main body of yarn windings, said spaced yarn windings being available for use as a transfer tail.

9. In a device for producing yarn packages having a transfer tail, the combination with means including a spindle for rotating a yarn package support, a spinning ring reciprocating relative to said spindle and a traveler carried by said spinning ring, of a slotted collar mounted on and rotating with said spindle for gripping a yarn end brought into contact with the periphery

- of said collar in the slot, and stationary guide means comprising a spiral having a plurality of convolutions cooperating with the yarn held by said gripping means adapted to receive the yarn end gripped in the slot of said collar in the outermost convolution and to direct the yarn through the remaining convolutions so as to cause the gripped yarn end to encircle the yarn package support and to wind thereon at a point spaced from the main body of yarn windings, said spaced yarn windings being available for use as a transfer tail.
10. In a device for producing yarn packages having a transfer tail, the combination with means including a spindle for rotating a yarn package support, a spinning ring reciprocating relative to said spindle and a traveler carried by said spinning ring, of a slotted collar mounted on and rotating with said spindle for gripping a yarn end brought into contact with the periphery of said collar in the slot, and stationary guide means comprising a spiral having a plurality of convolutions cooperating with the yarn held by said gripping means adapted to receive the yarn end gripped in the slot of said collar in the outermost convolution and to direct the yarn through the remaining convolutions so as to cause the gripped yarn end to encircle the yarn package support below the lowermost traverse stroke of the spinning ring and traveler and to wind on at the base of said yarn support at a point spaced from the main body of yarn windings, said spaced yarn windings being available for use as a transfer tail.
